UNITED STATES PATENT OFFICE

HENRY BRUCKER, OF NEWARK, NEW JERSEY, ASSIGNOR TO AMERICAN ALUMINUM
WARE CO., A CORPORATION OF NEW JERSEY

COMBINED CLOSURE AND POURING SPOUT

Application filed September 25, 1928. Serial No. 308,156.

This invention relates in general to a combined closure and pouring spout for receptacles or containers particularly for powdered or granular substances, which may be folded into the container to serve as a closure for an opening therein and can be swung outwardly to form a spout for pouring the contents of the receptacle through said opening.

One object of the invention is to provide a closure and pouring spout of the general character described embodying novel and improved features of construction whereby a secure hinged attachment of the spout to the receptacle may be obtained and the spout attached to the receptacle by a simple single operation.

Other objects are to provide a closure and pouring spout of this character which requires a minimum amount of material for its construction; to provide such a device having a novel and improved form of hinged connection for attaching the spout to the receptacle, and to obtain other advantages and results as will be more fully brought out by the following description.

Referring to the accompanying drawings, in which the same reference characters designate corresponding and like parts,

Figure 1 is a top plan view of a receptacle having a pouring spout embodying my invention applied thereto and shown in closed position.

Figure 2 is a similar view showing the spout in open position.

Figure 3 is a horizontal sectional view taken on the line 3—3 of Figure 1.

Figure 4 is a similar view taken on the line 4—4 of Figure 2.

Figure 5 is a sectional view through the container taken on the line 5—5 of Figure 2 and showing the closure and spout in side elevation and

Figure 6 is a plan view of the blank from which the closure and spout is formed.

Specifically describing the illustrated embodiment of the invention the pouring spout and closure is formed of a single piece of sheet metal 1 or other material approximately semi-circular as shown in Figure 6 of the drawings and bent along a radial line 2 to form two

portions 3 and 4, each of which is substantially a quarter sector the plane of which is arranged at approximately right angles to the plane of the other. At the outer end of the straight side of one portion, in the present instance the portion 4, is formed an integral hook 5 which is offset from the plane of the portion as at 6 and extends inwardly toward the other portion 3 as at 7. The corresponding edge of the other portion 3 has a substantially right angular integral flange 8.

The container 9 to which the spout is to be attached has a polygonal outlet opening 11 one side of which is extended in the form of a slot 12. In alignment with the adjacent side 65 13 of the opening which is at substantially right angles to the first-mentioned side, is an opening 14 of a size to receive the shank portion 6 of the hook 5.

The closure and spout is applied to the container by pressing the flange 8 thereof against the wall 10 of the container adjacent the slot 12 and simultaneously inserting the end of the hook 5 into the opening 14 with a sliding motion of the spout toward the slot 12, as indicated by dot and dash lines in Figure 5.

This action causes the flange 8 to slip through the slot 12 and into engagement with the inside of the wall 10 and at the same time the hook 5 is caused to pass through the opening 14 with the end thereof in engagement with the inner side of the wall 10, as shown by solid lines in Figure 5. The hook 5 and the end of the flange 8 next adjacent the portion 4 of the spout thus serve as a hinge connection for attaching the spout to the container, and the spout may be swung inwardly and outwardly of the container about the said hook

and end of said flange as an axis, the portion 3 serving as a guide. When the spout is pressed inwardly of the container the portion 4 overlies the opening 11 flat against the outside of the wall 10, as shown in Figures 1 and 3 of the drawings, so as to close said opening,

whereas when the spout is swung outwardly the opening 11 is uncovered and the two portions 3 and 4 cooperate to form a pouring spout as clearly shown in Figures 2 and 4 of the drawings. The flange 8 serves to limit

outward swinging of the spout by engagement with the inner side of the wall 10.

The particular construction and arrangement of the hook 5 and flange 8 with respect to each other and to the portions 3 and 4, enable the manufacture of the device with a minimum of waste material and the application of the device to a container with a single simple operation above described, whereby 10 the cost of manufacture and assembly is much smaller than with other known forms of spouts.

It is desirable to provide means for yieldingly holding the spout in open and closed 15 positions and for this purpose I may form the portion 3 with projections 15 and 16 preferably pressed from the metal and adapted to engage the outer and inner sides of the wall 10 adjacent the slot 12 to retain the spout in 20 open and closed positions, respectively. The resiliency of the portion of the wall adjacent the slot will permit said projections to slip into and out of the slot as the spout is moved from closed to open position and vice versa.

25 I am aware of such constructions as shown by Patents Nos. 1,375,725 dated April 26, 1921 and 1,347,446 dated July 20, 1920, and do not desire to be understood as attempting to claim such constructions.

30 Having thus described my invention, what I claim is:

1. The combination with a container wall having a polygonal pouring opening having two adjacent sides at substantially right angles to each other, a slot forming an extension of one of said two sides of said opening, and a hole in alignment with the other of said two sides, of a pouring spout comprising two quarter-sector shaped portions arranged at right 35 angles to each other, one of which has on its straight edge an integral hinge hook in a plane parallel to that of said portion and with its shank extending through said hole and its end extending toward the other portion sub- 40 angles to each other, one of which has on its straight edge an integral hinge hook in a plane parallel to that of said portion and with its shank extending through said hole and its end extending toward the other portion sub- 45 substantially parallel to said straight edge in engagement with the inner side of said container wall, the second-mentioned portion extending through said slot and having a hinge flange on its straight edge at substantially 50 right angles to the plane thereof in engagement with the inner side of said container wall.

55 2. The combination with a container wall having a polygonal pouring opening having two adjacent sides at substantially right angles to each other, a slot forming an extension of one of said two sides of said opening and a hole in alignment with the other of said two sides, of a pouring spout comprising two 60 quarter-sector shaped portions arranged at right angles to each other, one of which has on its straight edge an integral hinge hook in a plane parallel to that of said portion and with its shank extending through said hole and its 65 end extending toward the other portion sub-

stantially parallel to said straight edge in engagement with the inner side of said container wall, the second-mentioned portion extending through said slot and having a hinge flange on its straight edge at substantially 70 right angles to the plane thereof in engagement with the inner side of said container wall, said second-mentioned portion having integral projections one adjacent each end thereof to engage the outer and inner sides of 75 said container wall adjacent said slot to retain the spout in open and closed positions respectively.

HENRY BRUCKER.
